QUICK CHANGE PUNCH AND PUNCH
HOLDER

Arthur J. Boone, Jackson, Mich.

Application September 21, 1937, Serial No. 164,933

2 Claims. (Cl. 164—118)

The invention relates to a tool holder and more especially to a quick change punch and punch holder.

The primary object of the invention is the provision of a structure of this character, wherein the shank of the punch is milled and likewise the punch or holding plate so that the said punch can be changed with dispatch and be automatically lined up, irrespective of the shape of the 5 stamping end of the punch, whether oval, square or round, and the fitting of said punch with the holder plate being had through a plunger, which is injected into the milled areas of both the said shank and holder plate, the plunger being retained in the milled areas through lock screws.

Another object of the invention is the provision of a structure of this character, wherein a die can be readily and quickly fitted in place for coaction with the punch and properly aligned for 10 the cooperation with each other and thus avoiding the necessity for making a new line-up when changing the punches.

A further object of the invention is the provision of a structure of this character, wherein the same is novel in its make-up and assures quick changing of die and punch without liability of the loosening of the said punch or die in the use thereof.

A further object of the invention is the provision of a structure of this character, which is simple in its make-up, thoroughly reliable and efficient in operation, changeable with dispatch, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and 35 pointed out in the claims hereunto appended.

In the accompanying drawing:

Figure 1 is an elevation partly in section of a punch and die showing the invention applied thereto.

Figure 2 is a sectional view on the line 2—2 of Figure 1.

Figure 3 is a fragmentary elevation of the punch detached.

Similar reference characters indicate corresponding parts throughout the several views in the drawing.

Referring to the drawing in detail, A designates generally a punch and B a die cooperating therewith, the shank 10 of this punch being releasably fitted in a retainer body 11 and such punch at the stamping end thereof may be round, oval, square or other required shape or of any conventional form, the stamping end being indicated at 12. The retainer body 11 has provided therein a bore 13 receiving the shank 10 of the punch A.

The shank 10 of the punch A at one side thereof is formed with a socket 14 diagonally disposed and opening in such direction through one side of said shank while adapted to register with this socket 14 and aligned therewith is a way 15 which opens into an internally threaded circular pocket 16 which extends through the outermost face of the body 11, being parallel with the bore 13. Accommodated within the pocket 16 are removable inner and outer lock screws 17 and 18, respectively, 10 these having wrench engaging sockets 19 and 20, respectively, aligned with each other and accessible from without the pocket.

Insertable on removal of the screws 19 and 20 through the pocket 16 into the way 15 and the 15 socket 14 is a plunger 21 which fastens the shank 10 of the punch A in the bore 13 in the body 11 and in this manner the punch is made secure and is quickly detachable from the retainer body. The inner screw 17 retains the plunger 21 in the 20 way 15 and socket 14.

The die B in one side thereof has the diagonally disposed socket 22 opening through the periphery or side of the same while adapted to register and align with this socket 22 is an internally threaded bore 23 formed in the holder 24 for said die and this bore opens through the upper face of the holder. Insertable in the bore 23 to engage the socket 22 is a locking screw 26, being threaded in said bore 23 for the releasing of the same and 30 is accessible at the top of the holder 24. The screw 26 at its outer accessible end is formed with a wrench engaging recess 27 for convenience in working the screw home or its removal from the bore 23.

The mounting of the punch and the die assures a change of these in a minute's time and enables automatically the line-up therebetween.

What is claimed is:

1. A structure of the character described comprising a retainer body having a receiving bore for a punch, means entirely within said body for the holding of the punch in said bore, and lock screws fitting said body and maintaining the said means entirely within the body, the said screws 40 having wrench engaging sockets aligned with each other and accessible without the body and one screw being innermost with respect to the other screw.

2. A structure of the character described comprising a retaining body having an opening therein, a member removably fitting said opening, a single element retaining means wholly within the body, disposed for engaging the member in said opening at an acute angle thereto and accessible 50 from without the body, and adjustable means fitting the body and releasably holding the retaining means within said body.
